UNITED STATES PATENT OFFICE.

WILLIAM W. PRESTON AND EDWARD F. PRESTON, OF BISMARCK, MICHIGAN.

ICE-CREEPER.

SPECIFICATION forming part of Letters Patent No. 380,816, dated April 10, 1888.

Application filed October 19, 1887. Serial No. 252,816. (No model.)

To all whom it may concern:

Be it known that we, WILLIAM W. PRESTON and EDWARD F. PRESTON, both of Bismarck, in the county of Eaton and State of Michigan, have invented new and useful Improvements 5 in Ice-Creepers, of which the following is a full, clear, and exact description.

This invention more particularly relates to ice-creepers designed to be applied to rubber 10 overshoes; and it consists in an opening and closing or folding and reversible ice-creeper, and in various special constructions and combinations of parts making up the same, substantially as hereinafter described, and pointed 15 out in the claims.

Reference is to be had to the accompanying drawings, forming a part of this specification, in which similar letters of reference indicate corresponding parts in all the figures.

20 Figure 1 represents a view in perspective of the heel and rear portion of the sole of a rubber overshoe, as seen from beneath or inverted, with our improved ice-creeper applied, and as opened or turned over for use. Fig. 2 is a 25 similar perspective view, but showing the ice-creeper as closed upon the sole and out of use; and Fig. 3 is a longitudinal vertical section of like parts with the ice-creeper in its working position, as represented in Fig. 1.

30 A is the heel, and B the rear portion, of the sole of a rubber overshoe to which the ice-creeper is shown applied.

The main elements of our improved ice- 35 creeper are a shank or main plate, a turn-over pivoted or lever spur-frame, and a spring controlling the latter, the whole constituting a reversible ice-creeper capable of adjustment for use on or beneath the heel of the shoe, or for adjustment out of use against or folded up 40 within the hollow or shank of the sole.

C is the shank-plate, curved to conform on its surface longitudinally to the outer surface 45 of the portion of the sole B of the overshoe immediately in front of the heel A. This shank-plate is represented as constructed with an angling extension, b, at its rear end, constructed to bring the surface of said extension when attached to the shoe on a level with the under surface of the shoe-heel, and projecting 50 far enough thereon to give room for fastening

it firmly to the heel. This curved construction and angling extension of the main or shank plate makes said plate conform to the surface shape of the heel and the sole surface of the shoe immediately in front of the heel, 55 in order to utilize the spur-frame D of the device, as hereinafter described. Furthermore, said shank-plate C is constructed with a flange, c, on each side of its inner face, to form open bearings d for the journals of the pivot-bar e 60 of the spur-frame D, and to establish a recess for receiving within it under cover the spring S, which controls said frame. The pivot-bar e lies within a transverse groove, f, in the inner face of the shank-plate, connecting or terminating in the open bearings d for the journals of the pivot-bar in and through the flanges c. Rectangular countersunk holes are made in each end of the shank-plate C to receive rivet-fastenings h, thus holding the sole and 70 heel of the shoe to conform to the shape of said plate both when the spur-frame D is in and out of use.

The spring S, which occupies a longitudinal position within the shank-plate, is curved to 75 conform to the longitudinal curve of said plate, and is fastened to said plate near its frontend, as at i. Said spring extends back beyond the pivot-bar e and presses against the rubber of the front edge portion of the heel A, whereby 80 the spring is assisted in a measure by the resiliency of the rubber.

The turn-over lever-like spur-frame D has two side arms, k k, attached to the ends of the pivot-bar d, exterior of the side flanges of the 85 shank-plate C. These side arms are curved longitudinally, to conform the spur-frame D to the surface of the heel of the shoe when said frame is turned over onto the heel to put the spurs into use, and to conform to the shank of 90 the sole when said frame is not in use. The outer end of the spur-frame is of transverse-plate construction, connecting the side arms, k k, and has the spurs l l of the creeper on its outer corners.

95 The pivot-bar d of the spur-frame D is of flattened construction, and when in position for use in the transverse groove f the bearings in the side flanges of the shank-plate constitute the fulcrum for the side arms, k k, of the spur- 100

frame, and the spring S bears on the back of the pivot-bar d to control the spur-frame, which, by the construction of its arms and adjacent parts, as described, operates with a snap, and 5 is held securely in position both when thrown down or over onto the sole portion of the shoe, as shown in Fig. 2, to put the spurs out of action and the ice-creeper generally out of all projecting interference with the sole and heel 10 of the shoe when treading on the ground, and also when the spur-frame is reversed—that is, thrown over or back onto the heel of the shoe—to expose the spurs l l for use or action.

Arranged upon the outer surface of the front 15 end portion of the shank-plate C are stops or projections m, to prevent the spurs from cutting or marring the sole of the shoe when the spur-frame D is closed or shut down over the sole of the shoe out of use.

20 The rivets h, which secure the shank-plate C on the shoe, are split clinch ones—that is, their shanks are split—so that after being projected through the shoe to hold the creeper in place the split end portions of said shanks may 25 be flattened and spread out onto or over clinch collars or washers n n on the inside of the shoe. These rivets have a powerful clinch-draft in direction of their shanks, and not only form a ready means of attaching and detaching the 30 creeper, but hold the creeper securely in position against all strain. Any other fastenings, however, may be used, if desired.

An important feature in the construction of the ice-creeper as described is the binding of 35 the heel and sole together by the shank-plate having a heel-extension, as specified.

The pivot-bar of the spur-frame may be otherwise placed and secured; also the spring may be otherwise placed than hereinbefore de- 40 scribed. Thus the pivot-bar might be on the outside of the shank-plate and the spring outside over all without interfering with the re-

versibility of the spur-frame and without departing from the distinguishing character of the invention, as described. 45

Having thus fully described our invention, we claim as new and desire to secure by Letters Patent—

1. As an improved article of manufacture, an ice-creeper consisting of the curved shank 50 C, having opposite side flanges, c c, curved to fit the curve of the shoe in front of the heel and notched at their ends, as at d d, and the rearward extension, l, to rest on the shoe-heel, the spring S, secured and concealed within 55 the recess formed on the under side of the shank C, the swinging spur-frame having an angular cross - bar extending through the notches d under the spring, and curved side bars, k, at opposite sides of the shank, sub-stantially as set forth.

2. In an ice creeper, the shank C, curved to conform to shank of the shoe, and formed with the heel extension b and the curved side flanges, c c, forming a spring receiving and 65 concealing chamber and having notches in their edges near their rear ends, substantially as set forth.

3. The herein-described ice-creeper, consisting in the curved shank C, having a heel-extension, b, and notched side flanges, c, a spring concealed within the recess formed by said flanges, securing rivets at opposite ends of the shank, the stop m on the outer side of the front end of the shank, the swinging frame having 70 an angular cross-bar, e, curved side arms, k k, at opposite sides of the shank, and the spurs l at the outer corners of the frame, substantially as set forth. 75
